UNITED STATES PATENT OFFICE

170,087

BOX FOR CYLINDRICAL ARTICLES

Fred C. Harper, Waterville, Maine; Hazel H. Harper, executrix of Fred C. Harper, deceased, assignor to Keyes Fibre Company, Portland, Maine, a corporation of Maine

Application May 16, 1952, Serial No. 19,747

Term of patent 14 years

(Cl. D58—13)

To all whom it may concern:

Be it known that I, Fred C. Harper, a citizen of the United States of America, residing at Waterville, county of Kennebec, State of Maine, have invented a new, original, and ornamental Design for a Box for Cylindrical Articles, of which the following is a specification, reference being had to the accompanying drawing, forming part thereof.

Fig. 1 is a top plan view of a box for cylindrical articles, showing my new design;

Fig. 2 is a front elevational view thereof, partly in section, and taken on the line 2—2 of Fig. 1;

Fig. 3 is a side elevational view thereof, partly in section, taken on the line 3—3 of Fig. 1; and

Fig. 4 is a front elevational view of the box in closed position.

It is to be understood that the configuration of the unshaded portions throughout the article is the same as that depicted by the stippled portion.

What is claimed is:

The ornamental design for a box for cylindrical articles, as shown and described.

FRED C. HARPER.
